NEWELL B. PARSONS, OF LA GRANGE, JAMES E. WOODRUFF, OF CHICAGO, AND FRANK A. TIBBALS, OF RIVERSIDE, ILLINOIS, ASSIGNORS TO BELDEN MANUFACTURING COMPANY, OF CHICAGO, ILLINOIS, A CORPORATION OF ILLINOIS.

IGNITION-TIMER WIRING ASSEMBLY.

Application filed June 25, 1926. Serial No. 118,415.

This invention relates to wiring assemblies for use in connection with ignition timers such as are used on internal combustion engines, and more particularly to assemblies 5 for use in connection with timers such as are used on the engine of a Ford automobile.

The objects of the invention are—to provide means for conveniently connecting the necessary conductors to the binding posts of 10 a timer which is mounted in a comparatively inaccessible place on an engine; to prevent transposing of the conductors, to provide means whereby the ends of a plurality of conductors which are to be connected to the 15 timer may be mounted so as to be handled as a unitary structure, and collectively connected to the timer, and thereby eliminate the necessity of individual handling of each conductor; to provide means for retaining 20 the conductors adjacent the timer so as to avoid the danger of injury to said conductors by accidental engagement with a moving part of the engine; and to provide means for protecting the conductors to a large extent from 25 oil and grease, which ordinarily disintegrate the usual insulation used on the conductors.

Other objects are to provide an assembly 30 of the above described class which may quickly and easily be mounted on the timer to establish the necessary wiring connections without removing the timer shell from its place on the engine, and which will maintain the connections without the need of the usual binding post nuts; to provide a new and improved form of wire terminal which is particularly adapted to the present purpose, and which will not require the use of solder for fastening to the end of the wire.

Further objects of the invention are to provide 40 a wiring assembly which may be easily and inexpensively manufactured, which will be strong and rigid in construction, yet light in weight; and still further objects will become apparent when the following specification 45 is considered in connection with the accompanying drawing wherein a selected embodiment of the invention is illustrated, and in which

Figs. 1 and 2 are respectively plan and elevation views of the assembly connected to a timer of ordinary construction.

Fig. 3 is an elevation of the assembly disconnected from the timer.

Fig. 4 is a plan of the terminal of one of the wires and

Fig. 5 is a section on the line 5—5 of Fig. 4. Referring now to the drawings, 10 indicates a timer of common construction such as used on a Ford automobile engine. The timer 10 is provided in the present instance with 55 four projecting binding posts indicated at 11 which are insulated from each other and which are connected to suitable contact segments within the timer. The segments are held in place within the timer partly by means of nuts 12 threaded on the binding posts 11, which are screwed down against the outside of the timer casing, an insulating washer 13 being interposed therebetween to prevent the establishment of electrical contact between 60 the nut 12 and the timer casing. A suitable ear 14 is secured to the timer and adapted to receive an adjusting rod which is connected with the spark control lever in accordance with well known practice. The timer 10 is 65 mounted so as to be capable of being oscillated about its axis for the purpose of advancing or retarding the spark, which is also in accordance with well known practice.

The wiring assembly for use in connection 70 with a timer of the above described construction comprises a band or strip 15 preferably of insulating material which extends part way around the cylindrical portion 16 of the timer. The band 15 is preferably shaped to 75 be circular or arcuate in form and is provided with suitable apertures indicated at 17, through which the binding posts 11 of the timer may project. The strip is of sufficient 80 length to receive the required number of apertures and it is preferably of a width which 85 will require the provision of such means as a notch 14^a to receive the timer ear 14 in order 90 to permit proper connection of the wiring assembly and the timer. By this means, transposing of the conductors is prevented. Each 95 of the apertures 17 is provided with a wire terminal or contact member 18 which preferably comprises a tubular rivet-like structure 19 and wire holding means 20 as best shown 100 in Figs. 4 and 5.

In the last mentioned figures, it will be observed that the tubular rivet-like end or head end of the terminal or contact member 18, 105 comprises the tubular portion 21, having an integral top flange 22. Before application of

the contact member 18 to the strip 15, the tubular portion 21 of the contact member is of a length substantially as shown by the dotted lines in Fig. 5. When it is to be applied to the strip, the tubular portion 21 is inserted into the aperture 17 in the strip, and the projecting portion 23 of the tubular portion 21 is swaged outwardly so as to clamp the strip 15 between the top flange 22 and the 10 said swaged portion 23. The contact is thus securely mounted on the strip 15.

The top flange 22 is preferably provided with a recess in its under face, as indicated at 24, which is adapted to receive the bared end 15 25 of one of the conductors 26, which will be bent around the tubular portion 21, so as to form a substantially closed loop about the said tubular portion as best shown in Fig. 4. The wire holding means 20 comprises an extension 27 of the top shoulder 22, and is provided with ears 28 and 29 extending from either side thereof. These ears may conveniently be wrapped around the end of the conductor 26 adjacent the aforesaid closed loop 25 25. The conductor 26 in accordance with usual practice is covered with a suitable insulation, and the end of the conductor which is bared to form the said closed loop, is bared from a point which will leave the insulation 30 on the wire underneath the extension 27 so that the ears 28 and 29 may be wrapped thereon to prevent further baring of the wire, or unraveling of a braided covering, if such is used. The above described wire holding means 35 also serves to take up some of the strain which would otherwise be placed upon the closed loop 25.

The conductors 26 are each provided with terminals such as above described, and are 40 thereby fastened to the said strip 15. From said terminal fastening, the conductors are each disposed about the member 15 to a common junction as indicated at 30, from which point they are preferably braided together 45 and covered by a braided covering 31, which is provided with a tie-piece 32. The tie-piece 32 is an integral extension of the braided covering 31, and may conveniently be tied around the member 15 and the oppositely disposed conductors 26 as shown in Figs. 2 and 3. By 50 this means the conductors 26 are secured to the member 15 at the junction point so as to relieve the strain on the terminals 18. Braiding of the conductors together, from the junction 30 outwardly, serves to render the cable substantially self-supporting and eliminates the need of spring supporting means or other means for preventing excessive flexing of the wires at the junction whereby they would be 60 apt to be broken. Braiding of the wires however, does leave the cable sufficiently flexible to permit the necessary bending, but as noted above, prevents excessive bending.

The member 15 is preferably of such material 65 that it may be shaped to the desired

circular shape and will be resilient and have a spring-like tendency to retain this shape. It will thus be apparent that the member may be sprung so that it may be placed over the binding posts, which may readily be accomplished by placing one of the terminals in place on the proper binding post, and then pressing the portion of the member 15 intermediate the place terminal and the next one, so as to force the next one into place on the 75 next binding post. Due to the spring-like tendency of the strip 15 to assume its normal shape, the member will retain itself in position on the binding post and will not readily be disconnected therefrom. Since 80 the contact members or terminals 18 are tubular in form and are provided with a flange both on the inner and outer sides of the strip 15, there will always be sufficient contact between each of these terminals and its corresponding binding post to insure good electrical connection. However, binding nuts 33 may conveniently be threaded on the binding post 11 to tightly clamp the member 15 in 85 place over the timer and to establish a greater 90 area of contact between the contact members and the binding posts.

We have thus provided a wiring assembly which accomplishes the connection of a plurality of conductors to a plurality of timer 95 binding posts by means of a unitary structure which may be quickly and easily applied without the necessity of removing the timer from its mounting on the engine, and which may be readily oscillated with the timer to 100 advance or retard the spark.

We are aware that various changes in the form and construction of parts may be made without departing from the essence of the invention, and we therefore reserve the right to 105 make such changes as fall within the scope of the following claims.

We claim as our invention:

1. In combination, an ignition timer including a shell having a plurality of spaced 110 and relatively insulated terminals projecting therefrom, and a wiring assembly comprising a flexible band, having a plurality of openings extending therethrough in spaced relation to each other for respectively receiving 115 said terminals, a plurality of contact members insulated from each other and respectively secured to said band adjacent said openings so as to respectively engage said terminals, said band being expandable to permit its application to said shell, and a plurality of conductors respectively connected to said contact members.

2. In combination, an ignition timer including a shell having a plurality of spaced 125 and relatively insulated terminals projecting therefrom, and a wiring assembly comprising a flexible band, a plurality of contact members insulated from each other and secured to said band and spaced thereon so as 130

to respectively engage said terminals, said band being expansible to permit its application to said shell, a plurality of conductors respectively connected to said contact members, and means for preventing improper connection of the assembly contacts with the timer terminals.

3. The combination of a timer shell having a plurality of spaced and relatively insulated terminals projecting therefrom, and a wiring assembly comprising a resilient arcuate band adapted to embrace a portion only of said shell, a plurality of contact members insulated from each other and secured to said band and spaced thereon so as to engage said terminals, and a conductor permanently secured to each of said contact members.

4. In combination, an ignition timer including a shell having a plurality of terminals projecting therefrom, and a wiring assembly comprising a resilient arcuate band shaped to embrace only a part of said shell, a plurality of contact members insulated from each other and secured to said band and spaced thereon so as to respectively engage said terminals, a plurality of flexible conductors respectively connected to said contact members, disposed about said band to a common junction point and there secured to the band, said conductor being braided together as they leave the band whereby flexibility of the former is retained, but sharp bending adjacent the band is prevented.

5. In combination, an ignition timer including a shell having a plurality of terminals projecting therefrom, and a wiring assembly for connecting a plurality of conductors to said terminals and comprising a resilient band embracing only a part of said shell, a plurality of contact members insulated from each other and secured to said band, and spaced thereon so as to engage said terminals, a plurality of conductors respectively connected at their ends to said contact members, disposed about said band and grouped together at a common junction point, and means for securing said conductors to said band adjacent said junction and for preventing sharp bending of said conductors adjacent said band.

6. In combination, an ignition timer including a shell having a plurality of terminals insulated from each other and spaced around its periphery, and a wiring assembly for connecting a plurality of conductors to said terminals and comprising a resilient band of flexible material embracing a part of said

shell, a plurality of relatively insulated contacts on said band and respectively engaging said terminals and retained in said engagement by the resiliency of said band, and a plurality of conductors respectively connected to said contacts.

7. In combination, an ignition timer including a shell having a plurality of spaced and relatively insulated terminals projecting from its periphery, and a wiring assembly for connecting a plurality of conductors to said terminals and comprising a resilient arcuate band embracing a part of said shell and maintained thereon by its resiliency, a plurality of relatively insulated contacts secured to said band, and having means for respectively receiving said terminals, and a plurality of conductors connected respectively to said contacts.

8. In combination, an ignition timer including a cup-shaped shell having a plurality of circumferentially spaced and radially projecting terminals, and a wiring assembly for connecting a plurality of conductors to said terminals and comprising a resilient arcuate band of insulating material embracing a part of said shell and maintained thereon by its resiliency, a plurality of contacts secured to said band and apertured to receive said terminals and a plurality of conductors respectively connected to said contacts.

9. In combination, an ignition timer including a shell having a plurality of equally spaced terminals projecting radially therefrom, and a wiring assembly for connecting a plurality of conductors to said terminals and comprising a resilient arcuate band embracing a part of said shell, a plurality of contacts on said band respectively engaging said terminals, a plurality of conductors respectively connected to said contacts, and means for insuring correct relative engagement of said contacts with said terminals.

10. A wiring assembly for respectively connecting a plurality of conductors to the terminals of a standard Ford timer and comprising a flexible arcuate band adapted to embrace a part of the timer, a plurality of relatively insulated contacts secured to said band in relatively fixed position and arranged thereon so as to respectively engage said terminals, and a plurality of conductors respectively connected to said contacts.
